UNITED STATES PATENT OFFICE.

FLOYD W. SMITH, OF DAYTON, OHIO.

AUTOMOBILE-STARTER.

1,176,929.

Specification of Letters Patent. Patented Mar. 28, 1916.

Application filed April 19, 1915, Serial No. 22,276. Renewed February 11, 1916. Serial No. 77,793.

To all whom it may concern:

Be it known that I, FLOYD W. SMITH, a citizen of the United States, residing at Dayton, in the county of Montgomery and State of Ohio, have invented certain new and useful Improvements in Automobile-Starters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in starting mechanism for explosive engines and comprises a spring-propelled mechanism and spring rewinding mechanism to be hereinafter fully described in connection with the accompanying drawings.

The object of the invention is primarily to provide a type of spring-actuated starter which enables the transmission of one or more revolutions to the engine shaft in starting the same and which may be transmitted at the will of the operator.

Other objects and advantages are accomplished, such as effecting a rewinding of the motor spring, all due to a construction and arrangement of the mechanism as will appear from a particular description of the mechanism hereinafter set forth in connection with the accompanying drawings.

Referring to the accompanying drawings, Figure 1 is a horizontal sectional elevation of my improved engine starting mechanism; Fig. 2 is a sectional view on the line *b*—*b* of Fig. 1; Fig. 3 is a similar sectional view on the line *c*—*c* of Fig. 1; Fig. 4 is a similar sectional view on the line *d*—*d* of Fig. 1; Fig. 5 is a detail view of a modified form of locking means for the spring winding shaft; Fig. 6 is a detail view showing the means for cushioning the escapement member; and Fig. 7 is a detail side elevation of said escapement member through means of which the spring is released to apply the necessary force for the starting operation.

In a detail description of the invention, similar reference characters indicate corresponding parts both in the description and the drawings.

The starting shaft 1 is journaled in a suitable casing 3 and has connected to one end thereof the inner terminal of a convolute power spring 2 which is inclosed within a

drum 4 to a suitable point of which the other end of said spring is attached. The drum 4 has a suitable connection with an interiorly screw-threaded member or nut 5. The said drum 4 has also connected to the inner face thereof an outer ring 6 which forms one member of a roller clutch. The other member of said clutch consists of an inner member 7 which is stationary, being attached to the casing 3, and in the periphery of which there is a series of recesses 8 within which lie a series of gripping rollers 9. The other end of the starting shaft 1 has a chain wheel 10 running loose thereon and receiving a chain through means of which a transmission connection is made to the engine shaft; neither the chain nor the engine shaft being shown as these are well known elements and it is thought need no illustration or more than incidental mention. Also running loosely upon the shaft 1 is a gear 11 and an inner roller clutch member 12. These members 10, 11 and 12 are shown connected one with the other so that they move in unison. 80 Coöperating with the inner clutch member 12 is an outer clutch member 13 which is pinned or otherwise rigidly connected to the shaft 1 and between these two clutch members a series of gripping rollers 14 are located within recesses 15 formed in the periphery of the member 12. On the said shaft 1 adjacent to the clutch member 13, an escapement member 16 is mounted to rotate with said shaft, the mounting being by means of a series of feathers 17 which enter corresponding recesses in said member. The escapement member 16 has a peripheral cam groove 18 therein which extends to form a shoulder 19. Coöperating with said peripheral groove 18 is a pin 20 on an arm 27 which is loose upon a telescopic shaft 28 which fits over the reduced shaft portion 22'. The shaft portions 22 and 22' constitute one integral member and the telescopic shaft 28 is connected with an operating lever 29. The hub 27' of the arm 27 has a recess 30 forming a shoulder which is adapted to engage a plunger 31 carried in a pocket in an actuating member 32 and normally pressed outward by the spring 33. The actuating member 32 is mounted on the telescoped shaft 28 to rotate therewith.

The movement of the operating lever 29 from the first position to the second position, shown in Fig. 1, causes the plunger 31 to engage the shoulder formed by the re-

cess 30 and the continued movement of said lever 29 to the third position releases the pin 20 from the shoulder 19 of the cam groove in the escapement member and gives the shaft 1 over to the influence of the spring 2 at which time power is transmitted from said shaft to the shaft of the engine (not shown). It will be understood that the shaft 1 receives a complete rotation from the motor spring during which a floating screw 26 is moved to the extent of one thread by the nut 5. From this operation the lever 29 is moved from the second position to the third and to repeat the number of revolutions to be given the shaft 1 when necessary, such movement of the lever 29 from the second to the third position is repeated.

Within the escapement member 16 is placed cushioning springs 49 located between the said feathers 17. These springs are fixed to the feathers on opposite sides thereof and serve to cushion the escapement member when any excessive movement might be imparted thereto. The gear 11 meshes with a gear 34 which is fast upon a counter shaft 35 journaled in the casing 3. The shaft 35 is the rewinding shaft for the spring. The inner surface of the gear 34 is tapered to provide a clutching surface that coöperates with an inner clutch member 36 having a sleeve extension 37 which is recessed to receive an expansion spring 38 surrounding that portion of the shaft 35. The said spring exerts a force on the clutch member 36 to cause it to engage the gear 34. The said clutch member 36 and its sleeve extension are mounted to rotate with the shaft 35 but to have slidable movement thereon to disengage the clutch members. The spring 38 is maintained within the sleeve 37 by a washer 39 and a nut 40, the latter being threaded to the shaft 35 and of a diameter to permit the sleeve 37 to slide thereon. Engaging said sleeve is a stud 41 carried on a shifting lever 21 journaled on the enlarged portion 22 of the shaft 22'. The lever 21 terminates at its upper end in a sleeve 23 which is journaled upon said enlarged shaft portion 22. An arm 24 also extends from the sleeve 23 of the lever 21 and may be an integral part thereof. The lever 21, sleeve 23 and arm 24 move in unison. The arm 24 carries a roller 25 that lies in the path of the floating screw 26 mounted on the starting shaft 1 to rotate therewith but slidable thereon by means of a feather connection. This screw 26 and its coöperating parts control the rewinding of the motor spring in a manner to be presently described. The said screw 26 engages the elongated nut 5 and, as before stated, said nut is connected with or may be a part of the spring drum 4. The said screw 26 receives longitudinal movement from said nut 5 when the latter is

given over to the influence of said spring 2. The counter shaft 35 carries a pinion 42 which meshes with a gear 43 fast on the nut 5. The enlarged shaft portion 22 has a peripheral recess 44, best shown in Fig. 1, and the sleeve portion 23 of the arm 21 has a recess 45 which is adapted to receive a clutch-ball 46. The actuating member 32 carries an arc-shaped portion 47 which extends over the clutch-ball 46 and is provided with a recess 48 which is adapted to move out of alignment with the recess 44 in the shaft 22 and to clutch the ball 46 against the shaft portion 22.

When the recesses 44 and 48 are in alignment, the clutch-ball 46 will not lock the shaft 22 and at such time the inner clutch member 36 is thrown into engagement with the clutch surface of the gear 34 by the action of the spring 38. The counter shaft 35 is then driven from the shaft 1 to rewind the spring 2. When the part 47 of the actuating member 32 is in the position shown in Fig. 1, the arm 21 is held in position with the clutch member 36 separated from the gear 34 during which time the motor spring 2 is free to turn the shaft 1 to furnish the starting power.

In Fig. 5, I have illustrated a modification of the means for controlling the rewinding operation. Instead of the arm 21 and the parts coöperating therewith in controlling the clutch member 36, a series of toggle connections are incorporated. The slideable clutch member 36 has connected to the sleeve 37 thereof a shifting lever 50 pivoted at 51 to a suitable part of the casing. The said lever 50 is pivoted at 52 to the sleeve 37 and also to toggle levers 53 and 54, the adjacent ends of which are pivoted to the end of an angular lever 55. The angular lever 55 is pivoted at 56 and engaging the under surface thereof is a roller 57 the journal of which lies within an elongated slot 58 in the end of a lever 59. The lever 59 performs substantially the same function as the arm 21 and is pivoted at 60 to a suitable part. The lever 59 has a crank arm 61 and is operated from the floating screw 26 in a manner similar to the operation of the arm 24 and arm 21, hereinbefore described. The floating screw 26 engages an arm 61 which is fixed to the pivot 60 and as said screw engages the arm 61 the lever 59 is moved on one side of the pivot 56 of the angular lever 55. The roller 57 is mounted at the lower end of a spring 64, the other end of which is secured to a suitable part of the casing. When said roller 57 is on one side of the pivot 56, the toggle connection 53-54 shifts the clutch member 36 in one direction and when said roller is on the other side of the pivot 56, the said clutch member is shifted in the opposite direction and thus the engagement and disengagement of the rewind-

ing clutch members are controlled. The pin 20 operating in connection with the escapement member 16, moves the operating lever back to the second position. The purpose of the lever is to afford means for throwing the pin over to the opposite side of the cam groove thereby releasing the escapement member and allowing the starting shaft to make another complete revolution when necessary for starting purposes.

When the engine controls the rewinding shaft, the train of gears on the starting shaft 1, to-wit, 10 and 11, and the clutch member 12 will run loose relative to the shaft 1, owing to the disengagement of the clutches 12 and 13. After the engine becomes heated, the lever 29 is moved to the extreme left, as in Fig. 1, and the spring 38 will set the clutch member 36 thereby effecting a rewinding of the motor spring 2. During the rotation of the drum 4, the floating screw 26 will be caused, by the nut 5, to travel along the shaft 1 until it rocks the arms 24 and 21 thereby resetting the clutch member 36, at which time the motor spring 2 is completely rewound.

While I have with more or less particularity described my improved engine starting mechanism, I do not wish to limit myself to unnecessary details which may be varied more or less without departing from the underlying principles of my invention. These contemplate the employment of a spring motor and coöperating mechanism through the instrumentality of which one or more complete revolutions may be imparted to the starting shaft from the spring; also, means for controlling the rewinding of the motor spring at will or after the engine has gained sufficient momentum to be able to rewind the spring without danger of stopping the engine.

Having described my invention, I claim.

1. In a mechanism of the class specified, the combination with a starting shaft, and a motor spring connected thereto, of escapement mechanism adapted to permit said shaft to intermittently rotate, and means for transmitting the movement from said starting shaft to a driven shaft when the starting shaft is under the influence of said spring, substantially as described.

2. In a mechanism of the class specified, the combination with a starting shaft, and a motor spring adapted to actuate said shaft, of a transmission gear loose on said shaft, an escapement mechanism mounted on said shaft and adapted to permit said shaft to intermittently rotate, and means controlled by said escapement member whereby the said transmission gear is locked to the shaft when said shaft is actuated by the motor spring, substantially as described.

3. In a starting mechanism, the combination with a starting shaft, and a motor

spring for driving said shaft, of a loose transmission gear on said shaft, a clutch on said shaft connected with said gear, an escapement member mounted on said shaft and adapted to permit said shaft to intermittently rotate, and means for limiting the movement of said escapement member, substantially as described.

4. In a starting mechanism, the combination with a spring driven shaft, of an escapement member mounted on said shaft to rotate therewith, means coöperating with said escapement member controlling the amount of rotation given the shaft by said spring, a transmission gear loose on said shaft, and clutch members interposed between said escapement member and said gear by means of which the said gear is caused to move with the shaft, substantially as described.

5. In a mechanism of the class specified, the combination with a starting shaft, and a motor spring for driving the same, of an escapement member mounted on said shaft to rotate therewith and adapted to permit said shaft to intermittently rotate, a loose running transmission gear on said shaft, a clutch adapted to cause the gear and shaft to move in unison, and means coöperating with said escapement member and effecting a disengagement of said clutch whereby said shaft is limited in its movement, substantially as described.

6. In a starting mechanism, the combination with a starting shaft, and a spring motor for driving the same, of an escapement member rotatable with the shaft and a pin controlling the amount of movement imparted to said shaft by said spring, an operating lever, and means controlled thereby for placing the pin in a position to start said escapement member and said shaft after a complete rotation of the shaft, substantially as described.

7. In a mechanism of the class specified, the combination with a starting shaft, and spring motor for driving said shaft, of a transmission gear loose on said shaft, an escapement device moving with said shaft and limiting the amount of rotation thereof, means for synchronizing the movement of said gear and shaft, and means for rewinding the motor spring from said transmission gear after the starting movement of the shaft is completed, substantially as specified.

8. In a mechanism of the class specified, the combination with a starting shaft and a spring motor for driving said shaft, of a transmission gear loose on said shaft, a clutch controlling said gear when the spring controls the shaft, escapement devices controlling the extent of rotation imparted to said shaft by said spring, and means operated from said transmission gear for rewinding the spring at the completion of a

starting operation of said shaft, substantially as specified.

9. In a mechanism of the class specified, the combination with a starting shaft, a motor spring for driving said shaft, a drum inclosing said spring and to which said spring is attached, a normally loose running transmission gear on said shaft, means for limiting the amount of rotation of said shaft by said spring, a floating screw on said shaft, means carried on the spring drum to impart longitudinal movement to said screw, means for rewinding said spring, and means controlled by said screw for disconnecting the rewinding means, substantially as described.

10. In a mechanism of the class specified, the combination with a starting shaft, and a spring motor for driving the same, of a transmission gear loose on said shaft, a clutch controlling said gear and causing it to rotate with said shaft, an escapement device limiting the rotation of said shaft, rewinding mechanism for said spring includ-

ing a gear on the starter shaft rotatable by said transmission gear, a counter shaft, a clutch upon said counter shaft, a floating screw, and means interposed between said counter shaft clutch and said floating screw controlling the said counter shaft clutch, substantially as described.

11. In mechanism of the class specified, the combination of an intermittently rotatable starting shaft, a transmission gear thereon, a driving spring connected to said shaft, an escapement mechanism controlling the movement of said shaft, a rewinding shaft geared to said transmission gear, a clutch controlling the said gear connection, and means interposed between the rewinding shaft and said spring for rewinding said spring when said clutch effects an engagement between said rewinding shaft and said transmission gear, substantially as described.

In testimony whereof I affix my signature.

FLOYD W. SMITH.
